UNITED STATES PATENT OFFICE.

WILLIAM C. FREE, OF CHICAGO, ILLINOIS.

SEWING-MACHINE CABINET.

SPECIFICATION forming part of Letters Patent No. 759,363, dated May 10, 1904.

Application filed July 9, 1901. Serial No. 67,660. (No model.)

To all whom it may concern:

Be it known that I, WILLIAM C. FREE, a citizen of the United States of America, residing at Chicago, in the county of Cook and State of Illinois, have invented certain new and useful Improvements in Sewing-Machine Cabinets, of which the following is a specification.

This invention relates to that class of sewing-machine cabinets in which the machine-supporting platform is hinged in an opening in the top thereof and has a leaf located below and rigidly connected with such platform for closing the front of the same when its lid is shut. Its object is the production of a moderate-priced drop-head cabinet of very simple construction and easy operation; and it consists of certain new and useful features of construction and combinations of parts especially devised for those ends, all as hereinafter fully described, and specifically pointed out in the claims.

Referring to the accompanying drawings, which form a part of this specification, Figure 1 is a top plan view of a sewing-machine cabinet embodying my improvements. Fig. 2 is a section at the line 2 2 in Fig. 1 of parts there shown. Fig. 3 is a section at the line 3 3 in Fig. 1 of parts there shown. Fig. 4 is a section, also at the line 3 3 in Fig. 1, showing the platform and a machine which it is supporting lowered into the cabinet and the lid thereof closed. Fig. 5 is a front elevation of the cabinet closed.

Like letters of reference indicate corresponding parts throughout these several views.

The stationary portions of the cabinet consist, preferably, of two cases of drawers A, forming its ends, connected and secured together by means of a top A', having a central opening A² therein. Two inner end pieces A³ are also placed substantially parallel to each other against the inner sides of the cases of drawers A and secured to the under side of the top A'. To the insides of the inner end pieces A³ are secured stops A⁴, which serve to limit the downward swing of parts to be described hereinafter.

B is the lid of the cabinet and is connected to the upper side of the top A' thereof by means of hinges B'.

C is a platform hinged at C' in the opening A² in the top A' of the cabinet.

D is a leaf located below and rigidly connected with the platform C by means of the end and side connecting-pieces D' D² and 55 serves for closing the front of the cabinet when its lid is shut.

E is a bracket projecting downwardly from and rigidly secured to the under side of the top A'. 60

F F' are pulleys mounted at substantially right angles to each other on bearings F² F³ in the bracket E.

G is a longitudinal groove in the upper side of the top A' and the under side of its lid B. 65

H is a flexible connection, of leather, raw-hide, or chain, passing over the pulleys F F' and fast by one end H' to the rigid projection H² on the part D² and by the other end H³ to the under side of the lid B. 70

I is a sewing-machine mounted in the usual manner on the platform C.

J is a belt for driving the machine.

Figs. 1, 2, and 3 show the cabinet opened and the platform C thereof supporting the machine I in operative position, the open lid B serving as a counterweight to maintain the machine, through its platform C, in such operative position. 75

Fig. 4 shows the machine included within 80 the cabinet, the stops A⁴ thereon serving to limit the downward swing of the leaf D and therethrough support the platform C and machine I when not in use and its lid B closed.

What I claim as new, and desire to secure 85 by Letters Patent, is—

1. In a sewing-machine cabinet, the combination of a top having an opening, a lid hinged to the upper side of said top, a platform hinged in said opening to move at right angles to the 90 movement of the lid, a leaf disposed beneath said platform, end and side connecting-pieces rigidly joining the platform and leaf, a rigid projection on the front connecting-piece and disposed within and protected by the leaf, a 95 bracket depending from the under side of the top, pulleys mounted in said bracket at right angles to each other with one of said pulleys mounted in a recess in the top, said top having a longitudinal groove and the lid a corre- 100

sponding groove, and a flexible connection secured at one end to the under side of said lid and disposed in said grooves with its other end passed around said pulleys and secured to said 5 projection on the front connecting - plate of the leaf and having a bearing over the edge of said platform, all substantially as herein shown and described.

2. The combination with a table-top having 10 a hole through it, and a drop-leaf hinged to the front of said top and adapted to close said hole, with an extension-top hinged to said table on an axis at right angles to the axis of said drop-leaf, and a sheave and a roller carried by the

table on axes at right angles to each other, and 15 a cable secured at one end to said extension-top and at the other end to said drop-leaf between its ends and intermediately passing over said sheave and directly under said roller, substantially as described.

20 In testimony whereof I have signed my name to this specification in the presence of two subscribing witnesses.

WILLIAM C. FREE.
